UNITED STATES PATENT OFFICE.

CHESTER H. THORDARSON, OF CHICAGO, ILLINOIS.

SURGE-PROOF TRANSFORMER.

1,160,960.

Specification of Letters Patent. Patented Nov. 16, 1915.

Application filed October 6, 1913. Serial No. 793,787

To all whom it may concern:

Be it known that I, CHESTER H. THORDARSON, a citizen of the United States, and a resident of Chicago, in the county of Cook and State of Illinois, have invented certain new and useful Improvements in Surge-Proof Transformers; and I do hereby declare that the following is a full, clear, and exact description thereof, reference being had to the accompanying drawings, and to the characters of reference marked thereon, which form a part of this specification.

This invention relates to a novel method of protecting electrical machinery and devices used in electrical power transmission service, and especially high potential transmission lines, to safeguard the same from high potential disturbances or surges that may occur on the line and prevent the insulation between the turns of the winding of the electrical device or machine from being burned out, with the result of putting the device or machine out of commission. Such potential disturbances may occur from external sources, such as from lightning, or from internal potential changes on the line itself upon the opening of a circuit, or upon the short circuiting of the line or portion of the line in which the electrical device or machine is connected. Such rapidly changing magnetic flux has the effect of producing a potential in all the conductors that lie parallel to it, and, inasmuch as this induced potential is in proportion to the velocity of the surge and its magnetic density, it is evident that such induced pressure in the neighboring conductors, lying near thereto, may become enormously high.

The phenomenon of a break down in the insulation in high potential coils and transformers from an electro-magnetic surge is comparable to that of the receiving instrument of a wireless telegraphic system. The air gap in the coherer acts as an insulation in the manner of the insulation between the turns of the wire in a high potential transformer coil. The magnetic disturbances of a surge in an aerial system set up a potential on the conductor leading to the coherer that is sufficiently high to break through the air gap of the coherer or its insulation and thereby furnish a path for the battery current to flow to transmit a signal. Likewise, an excessive surge in the transformer acts to set up a high potential difference in the neighboring turns of its winding and when

it is sufficiently high to break through the insulation surrounding these conductors, the exciting potential and current from the magnetic field of the transformer immediately follow this path through the broken down insulation and very quickly heat the conductor to such an extent that the insulation surrounding it is charred. The surge energy breaks down the insulation in the neighboring turns which is quickly transmitted to each of the turns of the coil with the result of ruining the transformer.

It has heretofore been proposed to protect transformers and other electrical devices in high potential power transmission lines by placing choke or impedance coils in the line in series with the electrical devices or machinery to be protected. This method has not been found to meet the requirements for the reason that if the surge energy be very high, it may jump around or over the coil, and also because it is only efficient in checking to some extent or holding back the energy from the windings of the devices to be protected, so that the surge energy is allowed to surge back and forth on the line until it is dissipated as heat. Other practical economical disadvantages work against the use of a choke or impedance coil thus arranged. I propose, as a novel method of safeguarding electrical devices and machinery from such troublesome form of energy, and neutralizing its effect on the transmission system, to apply a few turns of special winding about the magnetic circuit of the transformer or equivalent part of an electrical device to which the invention may be applied, said winding being connected to the outside end or ends of the high potential winding of the transformer or other electrical devices or machinery. These special turns are intended to lie near or parallel to the high potential windings of the transformer and like windings in similar devices to be protected, and are insulated from each other to protect adjacent turns against the induced potential due to such external or internal disturbances. By placing an adjustable resistance on the second turn of this special winding, the surge energy induced in said winding may be dissipated in the form of heat in said external resistance, and any electro-magnetic energy due to the surge which passes still farther on may be absorbed in another resistance placed on the third turn, and so on. The turns of the said

special winding are made of progressively increasing cross section and capacity so as to safely take up the increasing potential impressed thereon by the surge disturbances, 5 and thereby protect the electrical device from an overcharge of potential, such as would break through the insulations between the turns thereof. The number of turns to be used, and the resistance to be employed in 10 connection therewith, may be adjusted to suit the conditions, and, in any event, will be proportioned as to protect the windings of the electrical devices from any expected maximum surge. The amount of surge 15 energy that can be thus dissipated may vary nearly as the square of the induced potential or many times higher than the operating potential of the magnetic circuit of the said electrical device.

20 I have shown in the drawings the adaptation of my invention to a high potential transformer, and have also shown two different forms of special winding referred to, but it will be obvious that the details of the 25 application of the invention may be considerably varied within the spirit and scope of the invention.

As shown in drawings:—Figure 1 is a vertical section of a high potential transformer 30 equipped with my surge protecting device. Fig. 2 is a fragmentary section of a transformer equipped with another form of surge protecting device. Fig. 3 is a fragmentary section taken on the line 3—3 of Fig. 2. Fig. 35 4 is a diagrammatic view illustrating the essential electrical elements of the device, apart from the mechanical embodiment thereof.

The magnetic circuit 10, herein shown as 40 of laminated construction, may be made of any suitable type, as also the low and high potential coils 11 and 12 wound therearound. In the present instance, said low and high potential coils comprise ribbon like conductors with the turns thereof insulated by strips of paper, or the like, such, for instance, as are shown in my co-pending application for U. S. Letters Patent, Serial No. 776,521 filed on the 30th day of June, 1913. The 45 magnetic circuit 10 embraces a core member 14 about which the low and high potential windings are wound, together with end members 15 and the side members 16 to complete the magnetic circuit. The low potential 50 winding is insulated from the core member 14 by an insulating layer 20 and is insulated from the high potential winding by a thicker insulating layer 21.

Arranged at one or both ends of the core 60 14 are the protective windings embodying my invention and designated, as a whole, by 22. One of such windings is shown diagrammatically in Fig. 4, and two different forms or modifications thereof are shown mechanically related to other parts in parts 1, 2 and

3. The said protective winding shown in Fig. 1 comprises five turns, designated respectively as *a*, *b*, *c*, *d* and *e*, with the turn *a* leading to a terminal 25 adapted for connection to the transmission line and with the last turn *e* connected to the adjacent turn of the high potential winding 12. In the form of the protective winding shown in said Fig. 1, the said turns are concentrically related. That is to say, the center turn *a*, 70 comprising a solid conductor, is inclosed within the next adjacent tubular turn *b*, with an insulating tube *a'* between them. The said turn *b* is likewise inclosed within the tubular turn *c* with an insulating tube *b'* between them. The said turn *c* is inclosed within the tubular turn *d* with an insulating tube *c'* between them, and the turn *d* is likewise inclosed within the tubular turn *e* with an insulating tube *d'* between them, the turn 80 *e* being in like manner surrounded by the insulating tube or sleeve *e'*. The said central and surrounding concentric turns are connected together to constitute a continuous coil or winding by the connecting conductors *a*², *b*², *c*², and *d*² as shown in Fig. 1, this arrangement constituting in effect a continuous spiral coil which is diagrammatically illustrated in Fig. 4 as a conventional winding or coil but of progressively increasing 90 diameter as it approaches the high tension winding. The said tubular conductors are preferably made of copper tubing of proper gage. Shunted between the second and third turns of this winding, as well as 100 the fourth and fifth turns, and between like related turns of a longer winding, if employed, are resistance elements 28, 28, shown diagrammatically in Fig. 4. In the mechanical application of these resistance elements 105 to the turns shown in Fig. 1, they each comprise upper and lower conductor plates 26, 27, connected at their peripheries by resistance elements 28. The plates associated with one pair of resistance elements, (the upper plates as herein shown) are in electrical contact with conductors *f*, *f'* that are shunted across the turns *b* and *c* of the protective winding by the conductors *b*³ and *c*³. The plates 26, 27 of the other pair herein 110 shown are likewise in electrical contact with other tubular conductors *f*², *f*³, respectively, which latter are in like manner shunted across the turns *d* and *e* of the protective 115 winding by the conductors *d*³, *e*³. These conductors of the resistance circuit are concentrically arranged, in the same manner as are the turns of the protective winding, the outer conductors being made hollow to inclose the 120 progressively smaller inner conductors and the central conductor which is connected to the terminal of the coil, is a solid wire. The several conductors are insulated from each other by tubular insulating sleeve shown. The outer conductor *f*³ is surrounded by a 125

insulating sleeve or tube f^4 , and is finally protected by a porcelain or other insulating inclosure f^5 that is screw-threaded in the top wall 30 of the casing 31 that incloses the 5 transformer elements, and also a body of cooling liquid, as oil, in which the transformer elements are immersed. The turn e of the protective winding is connected to the adjacent winding 12 by a conductor e^4 .

10 In the construction shown in Figs. 2 and 3, the turns of the protective winding 35, instead of being arranged concentrically with respect to each other, are arranged in flat-wise relation to each other, the initial turn g being of smallest cross section and the 15 turns toward the high potential winding being of progressively increasing cross section and capacity. This relation is best shown in Fig. 3 wherein g , g' , g^2 , g^3 and g^4 20 designate the respective turns of the protective winding, the initial turn g being made smallest, and the last turn g^4 of the winding being made widest to take care of the progressively increasing potential from 25 the initial to the last turn of the winding, in the same general manner as the concentric turns of the winding shown in Fig. 1. The several turns of the winding are insulated from each other by suitably heavy insulation. The group of windings is inclosed in 30 a heavy insulating sheath that also serves to hold them together. The turn g of the winding 35, last described, is adapted to lead to a suitable terminal of the transmission line. The several turns of the said protective winding are connected together to 35 complete the coil by the conductors g^6 , g^7 , g^8 and g^9 and are also connected by shunt conductors to the conductors h , h' , h^2 and h^3 of 40 external resistance circuits, herein shown as made of the same construction as in the type shown in Fig. 1.

The construction shown in Figs. 2 and 3, while efficient for the purpose designed, does 45 not reach the theoretical efficiency of the construction shown in Fig. 1, inasmuch as the potential generated between the turns of the windings acts from a given turn in all directions, and is, therefore, taken up in a more 50 efficient degree in the concentric relation than in the construction wherein the turns are arranged side by side, as shown in Figs. 2 and 3. The concentric form is also preferable for mechanical reasons inasmuch as it 55 is stronger and the windings are not subject to the liability of spreading apart under the electro-magnetic stresses which occur in a winding made of flat strips. The same electrical and mechanical advantages appear in 60 the arrangement of the terminal end of the protective winding and the conductors of the resistance circuits. However, it is to be understood that the latter construction may be varied within the broader aspect of the 65 invention

The connection of the several turns to each other and to the resistance circuit conductors is shown diagrammatically in order to clearly trace the connections. It will be understood, however, that all parts of the turns of the windings and said conductors at said connections will be suitably covered by heavy insulation and that the connections between said parts may follow any approved practice.

70 It will, of course, be understood that the protective winding may and usually will be arranged at both ends of the windings to be protected in order to protect the latter winding from surges entering the coil from either direction.

75 It will be understood that the details of applying my novel surge proof method or means to the protection of electrical devices or machines in transmission lines may be 80 varied within the scope of the invention, such details depending to an extent upon the specific character of the machine or device to be protected.

85 I claim as my invention:

90 1. The method of protecting the secondary winding of electrical transformers which consists in arranging in series with said winding a protective impedance winding and connecting an external resistance across the 95 turns of said protective winding.

95 2. A surge-proof electro-magnetic device comprising, in combination with a magnetic circuit, and a winding thereon, of a plurality of protective turns connected in series with 100 said windings, wound also upon said circuit, and means for dissipating the energy generated in said protective turns.

105 3. A surge-proof electro-magnetic device comprising, in combination with a magnetic circuit, and a winding thereon, of a plurality of protective turns of progressively increasing capacity connected in series with said windings and wound also upon said circuit and means to dissipate the energy generated 110 in said protective turns.

115 4. A surge proof electrical transformer comprising, in combination with the magnetic circuit thereof, and a high potential winding thereon, of a plurality of impedance windings in series with said high potential winding comprising a plurality of turns of progressively increasing capacity, and means to dissipate the energy generated in 120 the turns of said protective winding.

125 5. A surge proof electrical transformer comprising, in combination with the magnetic circuit thereof, and a high potential winding thereon, of a plurality of impedance windings in series with said high potential winding comprising a plurality of turns of progressively increasing capacity, and external resistance elements connected across 130 the turns of said protective windings.

6. A surge proof electro-magnetic device

comprising, in combination with a magnetic circuit, and a winding thereon, of a plurality of protective turns of progressively increasing capacity connected in series with said windings and also wound upon said circuit, and external resistance elements connected across the turns of the protective winding.

7. A surge proof electro-magnetic device
- 10 comprising, in combination with a magnetic circuit, and a high tension winding thereon, of an impedance winding consisting of a plurality of protective turns, arranged concentrically one within the other and of progressively increasing capacity and separated by tubular insulation and means to dissipate the surge induced energy generated in said protective turns.
8. A surge proof electro-magnetic device
- 20 comprising, in combination with a magnetic circuit, and a high tension winding thereon, of an impedance winding consisting of a plurality of protective turns, arranged concentrically one within the other and of progressively increasing capacity and separated by tubular insulation and external resistance elements connected across the turns of said protective winding.
9. A surge proof electro-magnetic device
- 30 comprising, in combination with a magnetic circuit, and a winding thereon, of a plurality of protective turns of progressively increasing capacity connected in series with said winding and wound also upon said circuit, and means to dissipate the energy generated in said protective turns, said protective turns being arranged concentrically one within another and separated by tubular insulation.
- 40 10. A surge proof electro-magnetic device comprising, in combination with a magnetic circuit, and a winding thereon, of a plurality of protective turns of progressively increasing capacity connected in series with the said winding and wound also upon said circuit, means to dissipate the energy generated in said protective turns and external resistances connected in shunt between the protective turns, the conductors of said external resistances being concentrically related with one conductor within another and suitably insulated.
- 50 11. A surge proof electro-magnetic device

comprising, in combination with a magnetic circuit, and a winding thereon, of a plurality of protective turns of progressively increasing capacity connected in series with the said winding and wound also upon said circuit, means to dissipate the energy generated in said protective turns, said protective turns being arranged concentrically one within another and separated by tubular insulation, and external resistances connected parallel between the protective turns, the conductors of said external resistances being concentrically related, with one conductor within another and suitably insulated.

12. A surge proof electro-magnetic device

70 comprising, in combination with a magnetic circuit, and a winding thereon, of a plurality of protective turns of progressively increasing capacity connected in series with said winding and wound also upon said circuit, and external resistances connected in shunt between the protective turns, the conductors of said external resistances being concentrically related, with one conductor within another and suitably insulated, and the resistance elements comprising conducting members that are severally attached to the tubular conductors of the resistance circuit, with resistance elements between them.

13. A surge proof electrical transformer

75 comprising, in combination with the magnetic circuit thereof and a high potential winding thereon, of a plurality of protective turns wound also on said circuit and in series with said winding, and means to dissipate the surge energy generated in said turns.

14. A surge proof electrical transformer

90 comprising, in combination with the magnetic circuit thereof and a high potential winding thereon, of a plurality of protective turns wound also on said circuit and in series with said winding, and external resistances connected to the said turns to dissipate the surge energy generated in said turns.

In testimony, that I claim the foregoing as my invention I affix my signature in the presence of two witnesses, this 1st day of October, A. D. 1913.

CHESTER H. THORDARSON.
